DESIGN FOR A DISPLAY CABINET

Roy L. Flannery, Chicago, Ill., assignor to The
 Boye Needle Company, Chicago, Ill., a corpora-
 tion of Illinois

Application June 28, 1947, Serial No. 139,998

Term of patent 14 years

(Cl. D80—11)

To all whom it may concern:

Be it known that I, Roy L. Flannery, a citizen of the United States, residing at Chicago, county of Cook, and State of Illinois, have invented a new, original, and ornamental Design for a Display Cabinet, of which the following is a specification, reference being had to the accompanying drawing, forming a part thereof, in which:

Figure 1 is a top plan view of a display cabinet, showing my new design; Fig. 2, a front view in elevation; Fig. 3, a side view in elevation; and Fig. 4, a top plan view taken as indicated from line 4—4 of Fig. 3.

I claim:

The ornamental design for a display cabinet, as shown.

ROY L. FLANNERY.
